Patented Feb. 11, 1919.

INVENTOR

JOSEPH G. BECKMANN

by Edward E. Longan Atty.

UNITED STATES PATENT OFFICE.

JOSEPH G. BECKMANN, OF ST. LOUIS, MISSOURI.

WATER-HEATER.

1,294,223.

Specification of Letters Patent. Patented Feb. 11, 1919.

Application filed August 17, 1916. Serial No. 115,380.

To all whom it may concern:

Be it known that I, JOSEPH G. BECKMANN, a citizen of the United States, and resident of St. Louis, Missouri, have invented certain new and useful Improvements in Water-Heaters, of which the following is a specification containing a full, clear, and exact description, reference being had to the accompanying drawings, forming a part hereof.

My invention relates to improvements in water heaters, designed primarily for domestic purposes, and my improvements are especially directed to the construction of the boiler or water heating body and its casing or shell, the object of my invention being to construct a boiler and to provide a casing therefor and arrange same to be heated by a gas or other vapor burner which will heat a maximum volume of water at a relatively high temperature in a minimum of time and without the usual "pounding" due to improper circulation.

With the above purposes in view, my invention consists in certain novel details of the construction and arrangement of parts hereinafter fully, clearly and concisely set forth in my specification, pointed out in my claims and illustrated by the accompanying drawing, in which—

Figure 1 is an elevation of a device embodying my improvements, with the door of the casing in an open position;

Fig. 2 is a vertical sectional elevation of the casing or shell having the boiler and burners removed and taken at right angles to Fig. 1;

Fig. 3 is a sectional plan view taken on the line 3—3 of Fig. 1, with the door of the casing in a closed position;

Fig. 4 is an enlarged fragmental sectional elevation illustrating the construction of the walls of the boiler; and

Fig. 5 is a sectional elevation of the base portion of the casing, showing the means for attaching a burner to the bottom of the base.

Referring by numerals to the accompanying drawings:

6 designates a fitting, which is arranged to be secured to a floor or other support and internally threaded to receive a pipe 7, the lowermost end of which pipe 7 is arranged for connection with a water service pipe (not shown). The uppermost end of the pipe 7 is externally threaded whereby to se-

cure thereto a union 8, which union connects the pipe 7 with a nipple 9 and which nipple connects the pipe 7 with the lowermost end of the boiler 10. The union 8 constitutes a support for the base portion 11 of the boiler casing, which base portion is substantially circular and has an integral bottom 12 extending approximately one-half ($\frac{1}{2}$) the diameter of the base. Integrally connected with the bottom 12 at its free margin and centrally of the base is a ring 13, which when the device is set up rests upon the union 8 and thus supports said base 11.

Arising from the upper end of the base is a flange 14 and extending upwardly beyond said flange is a number of ears 15, one only of which is shown in Fig. 2. The flange 14 is inset from the outer periphery of the base forming a shoulder 16, which shoulder constitutes a support for the casing or shell of the boiler.

By preference the casing comprises two sections of semi-cylindrical formation, the one section 17 arranged to rest upon the shoulder 16 of the base and be secured to the base by means of bolts extended through openings formed in the section 17 and through the ears 15, the other section 18 of the casing being hinged to the base, the lowermost hinge comprising a perforated integral extension 19 of the base and an integral outstanding lug 20 having a pin 21, as clearly shown in Fig. 1.

The reference numeral 22 designates the cap of the casing, which is provided with a flange 23 corresponding with the flange 14 of the base, except for its inversion when assembled, and with an outstanding shoulder 24 arranged to snugly fit the upper margins of the sections 17 and 18 of the casing. Like the base 11, the cap 22 is provided with ears 25 whereby to secure the section 17 of the casing to the cap. Formed centrally through the cap is an opening 26 through which a pipe 27 extends for connecting the upper end of the boiler 10 to a water tank or the like (not shown).

By preference I employ a short nipple 28 (shown only by dotted lines in Fig. 1) which connects directly with the boiler 10 and extends through the opening 26 and is connected with the pipe 27 by a union 29. By reason of the union 29 and the union 8, I am enabled to facilitate the assembling of the casing elements by exerting pressure on the cap and base by said unions thus holding

the casing elements assembled during their connection by the bolts 15 securing the one shell section to the base and the bolts connecting the said shell section with the cap.

5 Formed through the cap to one side of the opening 26 there is an opening 30, and surrounding the opening is an outstanding bead or collar 31 for connection with a flue (not shown) to carry off the unconsumed gases, 10 vapors, or other odors arising from the casing.

Extending laterally from the cap 22 is an ear 32, constituting a portion of the hinge connection between the section 18 or door 15 of the casing and the cap, the other portion of the said hinge connection being a lug 33, the companion of the lug 20 hereinbefore described.

In order to secure the door in a closed position, I provide the section 17 of the casing with an integral outstanding ear 34 and the section 18 or door with an integral outstanding hooked element or latch 35, which in closing the door automatically rides over 25 the ear 34 and seats thereover to lock the door, it being necessary for opening the door to release the hinged element 35 by elevating it over and from the ear 34. The boiler 10 is formed preferably by casting 30 as an integral unit comprising two tubular columns 36 and 37, the respective ends of which are united by return bends 38 and 39, the columns of said bends taking the form of an elongated "0".

35 The inner surface, as clearly shown in Fig. 4, is undulated in order to present to the water therein a maximum of surface as well as a retarding influence. The outer surfaces of the columns, as well as the return bends of the boiler, are provided with 40 spaced annular outstanding fins 40, certain of which, extending between the columns, are integrally united whereby to lend rigidity to the boiler as well as to constitute additional means to retard and circuitously deflect the heat units in their traverse of the casing. Each of these fins 40 constitutes a heat-absorbing body, and it is obvious that when the fins are heated they retain heat 45 for a considerable period of time, thereby economizing the heating of successive quantities of water.

The fins on the vertical columns are arranged at right angles to the axes of the 55 columns, while the fins on the return bends 38 and 39 are in radial disposition.

In addition to the fins as means for deflecting the traverse of the hot gases or vapors, I form integrally with the sections 60 17 and 18 of the casing deflectors 41 and 42, each of which has an area of substantially one-half ($\frac{1}{2}$) the diameter of the casing, and each being provided with notches 43 to surround the columns of the boiler.

65 Formed integrally with the cap and ex-

tending downwardly therefrom in a vertical position and to one side of the flue opening 30 is a deflector 44, the lowermost end of which approximates the fins 40 of the boiler. Extended upwardly through the 70 open side of the base 11 is a pair of vapor burners 45, preferably of the Bunsen type, each burner being provided with an ear 46 for connection with the bottom 12 of the base, as clearly shown in Fig. 5. These 75 burners are each equipped with mixers 47 and valves 48, the specific structures of which form no part of my invention. The valves are connected by means of a Y-fitting 49 to the gas service pipe 50, a portion only 80 of which is shown in Fig. 1. It will be obvious from this showing that when the burners are ignited the flames therefrom will produce in a minimum of time a great 85 volume of heat units which rise to the deflector 42 and contact the entire surface of the boiler or water heating body, including all of the fins 40. Meeting the deflector 42, the heat units are all deflected to one side of the casing, thereby retarding their motion. 90 The heat units then rise and are then shifted in their course by the deflector 41, where they again rise and are retarded by the deflector 44 before reaching the flue opening 30. In this manner there is produced a relatively long traverse for the products of combustion and hot gases through the casing, and thus cause the heat units to intimately 95 hug the walls of the boiler and be absorbed by the fins thereof.

100 The water is fed to the boiler through the pipe 9, and by reason of the increased capacity of the column of the boiler over the pipe 9, the flow of water is much slower through said columns than through its supply pipe 9, and by reason of the undulated surface of the heat absorbing fins, the water is heated in a rapid manner and in a considerable volume. In order that there be a minimum of escape of heat units at the 110 joints of the casing, I have provided the lap-flanges 51, as clearly shown in Fig. 3.

115 It is to be observed that the upper faces of all of the fins on the columns proper are arranged horizontally, whereby to collect water of condensation and hold such water to prevent it from dropping through the casing and soiling the floor or foundation beneath the heater, thereby dispensing with a drip pan.

120 Having thus described my invention, what I claim as new therein and desire to secure by Letters Patent of the United States, is:

1. A boiler comprising twin columns and integral return bends uniting the columns, 125 outstanding fins on the outer surface of the boiler, and an undulated surface within the boiler.

2. A boiler comprising twin columns, integrally united by reverse bends, a water 130

inlet in the one bend and a water outlet in the other bend, and an undulated surface within the boiler.

3. A boiler constructed as an integral unit, comprising tubular columns, united by reverse bends, outstanding fins on said columns and reverse bends, certain of which fins between said columns are connected to lend rigidity to the boiler and to retard and deflect a heating medium and means whereby the boiler may be connected with water inlet and outlet pipes.

4. In combination with a water heating body, comprising tubular columns united by reverse bends, means for connection with water inlet and outlet pipes and heat absorbing fins, certain of which fins between said columns are connected to lend rigidity to the

body and to serve as deflectors for a heating medium, a casing comprising hinged sections serving as side walls therefor, a cap and a base, a source of heat extended through said base, there being an outlet for the heat in said cap, deflectors carried by said hinged sections and notched to accommodate said columns and a deflector carried by the cap in advance of said outlet with respect to the course of the heat. 20 25

In testimony whereof, I have signed my name to this specification, in presence of two 30 subscribing witnesses.

JOSEPH G. BECKMANN.
